ADJUSTABLE LADDER

Edward C. Obermeyer, Grand Rapids, Mich.

Application May 29, 1941, Serial No. 395,865

5 Claims. (Cl. 228—63)

The device forming the subject matter of this application is a step ladder, adapted for indoor use or for outdoor use, novel means being provided for holding the legs of the ladder at adjusted lengths, so that the ladder will stand upright, even though the underlying supporting surface may be vertically irregular.

It is within the province of the disclosure to improve generally and to enhance the utility of devices of that type to which the present invention appertains.

With the above and other objects in view, which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

In the accompanying drawings:

Fig. 1 shows, in front elevation, a step ladder constructed in accordance with the invention;

Fig. 2 is a side elevation of the step ladder;

Fig. 3 is a fragmental vertical sectional view, disclosing one of the grips and associated parts;

Fig. 4 is a transverse section of Fig. 3;

Fig. 5 is a transverse section on the line 5—5 of Fig. 1;

Fig. 6 is a front elevation illustrating one of the many positions which the parts of the ladder may assume, when it is used on an irregular surface;

Fig. 7 is a sectional detail disclosing one of the spacers and attendant parts;

Fig. 8 is a front elevation showing a modified form;

Fig. 9 is a front elevation of the ladder delineated in Fig. 8, the parts being arranged as they will appear when the ladder is set up on an irregular surface;

Fig. 10 is a side elevation of the ladder shown in Fig. 8;

Fig. 11 is a vertical sectional view disclosing details of one of the leg structures;

Fig. 12 is a transverse section on the line 12—12 of Fig. 11;

Fig. 13 is a transverse section on the line 13—13 of Fig. 9;

Fig. 14 is a sectional elevation showing one of the grips and associated parts.

Figures 1 to 7 disclose a ladder adapted primarily but not necessarily for indoor use. The ladder includes a platform 1. The rear legs or

prop of the ladder are designated generally by the numeral 2.

The rear legs 2 comprise upper sections 3, which are hinged at 4 to the platform 1. The upper sections 3 of the rear legs carry the usual foldable tool support 5. The upper sections 3 are connected by cross braces 6.

The lower sections 7 of the rear legs 2 are disposed inwardly of the upper sections 3. The lower sections 7 may be rubber shod, as shown at 8.

Guides 9, which are U-shaped, are secured to the lower sections 7, and U-shaped brackets 10 are secured to the upper sections 3. The upper sections 3 are slidably mounted in the guides 9, and the lower sections 7 are slidably mounted in the brackets 10.

Figures 3 and 4 show that cam lever grips 11 are pivotally mounted at 12 in the brackets 10. Pull springs 14 connect the grips 11 with the upper leg sections 3 and cause the grips 11 to bind the lower leg sections 3 and 7 together against relative longitudinal sliding movement.

The forward legs of the ladder are designated generally by the numeral 15 and form a tread member. The forward legs 15 include upper sections 16, which are hinged at 17 to the platform 1. There are spacers 19 on the outer surfaces of the upper leg sections 16. The spacers 19 have openings 20 which receive the heads of bolts 21 that retain treads 18 between the leg sections 16. Guides 20, of U-shape, are secured to the upper leg sections 16.

The lower sections of the forward legs 15 are marked by the numeral 21. They are disposed outwardly of the upper sections 16 and can slide for adjustment in the guides 20, in contact with the spacers 19.

The numeral 22 designates a lever of the first order, fulcrumed at 23, intermediate its ends, on one of the treads 18. Links 24 are provided, and are pivoted at 25 to the ends of the lever 22 and to the lower ends of the sections 21.

Referring to Fig. 5, hook-shaped grips 26 extend in opposite directions around the leg sections 21 and 16. The grips 26 are pivotally mounted, at 27, intermediate their ends, on the upper leg sections 16. The grips 26 include inwardly projecting handles 28 located behind one of the treads 18. Pull springs 29 are connected to the handles 28 and to the upper sections 16 of the forward legs 15.

By slackening away the cam lever grips 11 of Fig. 3, either or both of the lower sections 7 of the rear legs 2 may be adjusted up or down, and

when the grips 11 are released by an operator, the pull springs 14 cause the grips to bind the leg sections 3 and 7 together, thereby holding the rear legs 2 at any lengths to which they may have been adjusted.

By means of the handles 28, the hold of the grips 26 may be released, and one or both of the lower front leg sections 21 may be moved upwardly or downwardly. When the handles 28 are released by an operator, the springs 29 react and cause the grips 26 to bind the leg sections 16 and 21 tightly together, thereby holding the leg sections 21 at any height to which they may have been adjusted.

The lever 22 and the links 24 cause the lower sections 21 of the forward legs 15, each, to move upwardly when the other leg section moves downwardly, an observation which will be understood readily when Fig. 6 is noted. The construction is such that the ladder can be used even though there are many irregularities in the supporting surface.

Notwithstanding the fact that the lever 22 automatically adjusts the effective lengths of the leg sections 21 when there are irregularities in the surface of the soil, the soil may be more yielding beneath one leg section than beneath the other, and the operator may wish to assure himself, before he ascends the ladder, that it will maintain an upright and proper position under his weight. It will be noted that the end portions of the lever 22 extend outwardly and laterally beyond the leg sections 21 to serve as members upon which he may throw his weight, thereby advancing one leg section into the ground until it comes to a firm seat.

Passing to the form depicted in Figs. 8 to 14, there is shown a step ladder adapted primarily but not necessarily for outdoor use.

The ladder comprises a platform 30, a rear leg or prop being designated generally by the numeral 31. The numeral 32 marks the downwardly converging members of the upper section of the rear leg 31. The parts 32 of the upper leg section are hinged as shown at 33 to the platform 30.

At their lower ends, the downwardly converging members 32 of the upper section of the rear leg 31 are joined together by straps 34, which define a lower guide.

Above the straps 34, the downwardly converging members 32 of the upper leg section are connected by straps 35, which define an upper guideway. Adjacent to one of the members 32 of the upper leg section, a filler block 36 is secured between the straps 35, as shown in Figs. 11, 12 and 14.

The member 32 (Figs. 12 and 14) of the upper leg section which is remote from the filler block 36, is received within the forked head 31 of an inwardly projecting grip 38, the head of the grip being pivoted at 41 to the aforesaid member 32. The grip 38 is drawn upwardly by a pull spring 39, the lower end of the spring being secured to the grip 38, and the upper end of the spring being secured to the adjacent member 32 of the upper leg section. An upright releasing lever 40 is fulcrumed intermediate its ends, at 42, on the straps 35, the lower end of the releasing lever bearing on the grip 38.

The numeral 43 marks a lower leg section, mounted for vertical adjustment in the lower guideway formed by the straps 34, and in the space between the straps 35, in contact with the filler block 36. Under the impulse of the spring 39, the grip 38 bears against the lower leg section

43 and holds it in any position to which it may have been adjusted vertically, it being possible to release the hold of the grip 38 on the lower leg section 43, by manipulating the lever 40.

5 A forward leg structure or tread member is provided, and is designated generally by the numeral 51. The forward leg structure 51 embodies parallel stiles 52, connected by treads 53. The stiles 52 are hinged at 54 to the platform 30. 10 The members 32 of the rear leg structure, and the stiles 52 of the forward leg structure are joined together by cross rods 56, a rule joint brace 55 extending between the cross rods.

Radius arms 57 are hinged at 58 to the outer 15 sides of the stiles 52, for lateral swinging movement. Lower leg sections 59 are supplied, and are equipped at their upper ends with guides 60, wherein the radius arms 57 are received slidably. At their lower ends, the radius arms 57 are equipped with guides 61, wherein the lower leg sections 59 are slidably received.

20 Brackets 72 of U-shape are secured to the radius arms 57 and receive the lower leg sections 59 slidably. Grips 62 of U-shape are provided, and are pivotally mounted at 63 within the brackets 72. The grips 62 have inwardly projecting handles 64, which extend past each other at their inner ends, and are located behind one of the treads 53. The upper ends of pull springs 30 65 are connected to the handles 64 of the grips, the lower ends of the springs being connected to the stiles 52. The tendency of the springs 65 is to cause the grips 62 to press the radius arms 57 and the lower leg sections 59 together, thereby holding the parts 57 and 59 against relative longitudinal movement.

25 In order to lengthen the effective height of the rear leg structure 51, the releasing lever 40 is manipulated, thereby breaking the hold of the 40 grip 38 on the lower leg section 43, it being possible to adjust the lower leg section vertically. When the lever 40 is set free, the grip 38 resumes its hold on the leg section 43, responsive to the spring 39.

30 45 By manipulating the grips 62, through the instrumentality of the handles 64, the lower leg sections 59 may be set free for longitudinal adjustment.

The numeral 44 designates a lever of the first 50 order, fulcrumed intermediate its ends, at 45, on one of the treads 53 that connect the stiles 52. The lever 44 is pivoted at its ends, as shown at 47, to the lower leg sections 59.

The lever 44 constitutes a brace connection between the leg sections 59, of such nature that when one of the leg sections is slid upwardly, the other leg section will be slid downwardly, without attention on the part of the operator, the lever 44 automatically fixing the spread of the lower sections 59.

60 65 The device forming the subject matter of this application will be found thoroughly effective, in either of its forms, to consummate the objects set forth in the opening portion of the specification, as well as others incident to the operation of the structure involved.

Having thus described the invention, what is claimed is:

1. A step ladder comprising a platform, a prop hinged to the platform, a tread member hinged to the platform and comprising pairs of upper and lower sections, the members of each pair being slidably assembled for longitudinal adjustment, a hook-shaped grip extended about the upper and lower sections of each pair and including

an inwardly-projecting releasing handle, means for fulcruming each grip intermediate its ends on one of the upper sections, and spring means constraining each grip to bind the upper and lower sections of one pair together, against relative longitudinal movement.

2. A step ladder comprising a platform, a prop hinged to the platform, a tread member hinged to the platform and comprising upper and lower sections assembled for relative longitudinal sliding adjustment, a lever fulcrum-supported intermediate its ends on the upper sections, pivoted links connecting the ends of the lever movably to the lower sections, to cause each lower section to move upwardly when the other lower section is moved downwardly, and mechanism for releasably holding each lower section against longitudinal movement with respect to the corresponding upper section, the lever comprising end portions which extend outwardly and laterally beyond the sections to serve as members upon which the operator can throw his weight to adjust the effective length of either section, should the soil be more yielding beneath one section than beneath the other.

3. A ladder comprising upper leg sections, treads disposed between the sections, securing devices connecting the treads with the sections and having heads disposed outwardly of the sections, spacers secured to the outer surfaces of the sections and defining openings receiving the heads, the spacers being at least as thick as the heads, lower leg sections, means for mounting the lower leg sections for longitudinal sliding movement on the spacers, said means being secured directly to the upper sections, and independently

5 of the spacers, whereby the spacers may be renewed without disturbing said means, the spacers constituting wear strips and serving to space the lower sections the more widely apart, thereby to increase the stability of the ladder, and prop means assembled with the upper sections.

4. A ladder comprising a tread member including upper and lower sections assembled for relative longitudinal sliding adjustment, a lever fulcrum-supported intermediate its ends on the upper sections, pivoted links connecting the ends of the lever movably to the lower sections, to cause each lower section to move upwardly when the other lower section is moved downwardly, and mechanism for releasably holding each lower section against longitudinal movement with respect to the corresponding upper section, the lever comprising end portions which extend outwardly and laterally beyond the sections to serve as members upon which the operator can throw his weight to adjust the effective length of either section, should the soil be more yielding beneath one section than beneath the other.

5. A ladder comprising a tread member including pairs of upper and lower sections, the members of each pair being slidably assembled for longitudinal adjustment, a hook-shaped grip extended about the upper and lower sections of each pair and including an inwardly-projecting releasing handle, means for fulcruming each grip intermediate its ends on one of the upper sections, and spring means constraining each grip to bind the upper and lower sections of one pair together, against relative longitudinal movement.

35 EDWARD C. OBERMEYER.
